INDIVIDUALLY WRAPPED BAG PACKAGE

Ernst Rudolf Anders, Dresden, Germany, assignor to Millie Patent Holding Co., Inc., New York, N. Y., a corporation of New York

Application June 15, 1935, Serial No. 26,748

2 Claims. (Cl. 206—46)

This invention relates to bags of tea and other essence containing products and more particularly is directed to an individually wrapped tea bag package or similar article formed with a sanitary wrapper.

Among the objects of the invention is to provide a novel sanitary individually wrapped tea bag package or similar article which package wrapper shall comprise few and simple parts forming an 10 inexpensive article of neat and attractive appearance, which wrapper shall be easy and cheap to apply, and which article shall be efficient and practical to a high degree, in use.

Another object of the invention is to provide 15 a little package consisting of an individual service tea bag and wrapper therefor, the organization being such that the tea bag is retained in the wrapper in relatively fixed position so as to minimize movement of the tea bag within the wrapper 20 and thereby to minimize the possible pulverization of the tea contents of the bag.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims:

30 In the accompanying drawing, in which there is shown possible illustrative embodiments of this invention.

Figs. 1, 2 and 3 are perspective views showing the successive steps in applying the wrapper to a tea-bag in forming the package embodying the invention;

Fig. 4 is a front elevational view of the completed individually wrapped tea-bag package embodying the invention;

40 Fig. 5 is a sectional view taken on lines 5—5, in Fig. 4;

Fig. 6 is a top plan view of the package shown in Fig. 4, and

Fig. 7 is a front elevational view of a modified 45 form of the invention showing the string-handle and tag enclosed in the package.

Referring to the drawing, 10 denotes a sheet of wrapping material, such as opaque, translucent or semi-translucent paper, or so-called "cellophane" which sheet when opened flat has the sides on the opposite ends shaped to converge or taper, as shown in 10a. The tea bag 11 may be of any well understood construction and as here shown is of the pouch type having a string handle 12 anchored under a suitable form of clo-

sure such as metal closure ring 13 applied to the gathered cover of the pouch bag 11, said string handle 12 being terminated by a tag 14 secured by staple 15.

In forming the improved package, the sheet 10 has a suitable adhesive applied to the edge portions thereof as at 10b and the tea bag 11 is placed on the sheet 10 with the string handle 12 and tag 14 outwardly extending as shown in Fig. 2. The sheet 10 is then folded over on itself 10 across its mid-portion as along fold line 10c (indicated in dot and dash line in Fig. 2). The edge portions on both ends of sheet 10 are brought in register and pressed together until the adhesive applied at 10b sticks, and completely encloses the tea bag 11 in the wrapper 10, with the string handle 12 extended outside at the shortest edge of the taper 10d as shown in Figs. 3 to 6, inclusive.

From the above description and drawing it is apparent that this improved form of package 20 can be made without any person's hands touching the tea bag pouch 11 and is therefore sanitary.

To remove the enclosing wrapper 10, the package is simply held at the fold portion 10c and by exerting a pull on the string handle 12, the gathered closed end of the pouch will readily rip open the seam at the edge 10d and without touching the pouch 11 it may be immersed in boiling water to brew the tea in the well understood manner.

In the modified form of the invention shown in Fig. 7, the string handle 112 of the bag may first be wound up as at 112a on the gathered portion of the pouch 111 and the tag 114 is preferably positioned to lie flat against the pouch before sealing the same in the wrapper 10. The tea bag may be removed from the wrapper 10 by simply tearing the latter and removing same by holding the tag 114 or string 112.

It should be noted that in both forms of the invention the tapered end closure of the tea bag is disposed substantially within the tapered end of the wrapper. This relationship taken together with the substantially flattened condition of the bag and wrapper and together with the stiffness imparted to the entire package by the adhesively secured marginal portions serves to retain the tea bag in a substantially fixed position in the wrapper and to minimize the movement of the bag within the wrapper. This feature of the present new article of manufacture serves to reduce and minimize the possible pulverization of the tea in the bag during the subsequent handling thereof.

It will thus be seen that there is provided articles in which the several objects of this invention are achieved and which are well adapted to meet the conditions of practical use.

5 As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent

15 1. As an article of manufacture, a thin flat package comprising a flattened essence containing bag of loosely woven textile fabric formed with a tapered gathered closure and a wrapper enclosing said bag, said wrapper being formed of a single elongated sheet folded midway its 20 ends and having two superposed coincident walls, each wall having an oblong portion and an outwardly extending tapered end portion, the contiguous superposed marginal portions of said walls being adhesively secured together to form 25 a substantially flat structure, said adhesively secured edges serving as stiffening means for retaining said bag and wrapper in flattened condition, the dimensions of the wrapper being sub-

stantially greater than the dimensions of the bag, the bag being positioned within the wrapper with the tapered gathered closure extending in the direction of and disposed within the tapered end of the wrapper and cooperating therewith 5 to minimize the movement of the bag and to retain the same in a substantially fixed position in the wrapper.

2. As an article of manufacture, a package comprising an essence containing bag of loosely woven textile fabric formed with a gathered closure, a string handle attached to and extending from said gathered closure, and a wrapper enclosing said bag, said wrapper being formed of a single elongated sheet folded along the line 15 midway its ends and having two superposed coincident walls, each wall having an oblong portion and a tapered end portion, the contiguous superposed edges of said walls being adhesively secured together, the bag being positioned within 20 the wrapper with the gathered closure of the bag extending in the direction of the tapered end of the wrapper and the string handle extending through and beyond the tapered end of the wrapper, so that a pull on the string causes the 25 gathered closure of the bag to rip open the seam of the wrapper.

ERNST RUDOLF ANDERS.
